CROSSING SIGNAL

Filed Sept. 5, 1925

2 Sheets-Sheet 2

UNITED STATES PATENT OFFICE.

CHARLES GRAGERT, OF ADA, MINNESOTA.

CROSSING SIGNAL.

Application filed September 5, 1925. Serial No. 54,762.

To all whom it may concern:

Be it known that I, CHARLES GRAGERT, a citizen of the United States, residing at Ada, in the county of Norman and State 5 of Minnesota, have invented certain new and useful Improvements in Crossing Signals, of which the following is a specification.

This invention relates to signals and pertains particularly to railroad crossing signals.

The primary object of this invention is the provision, in a manner as hereinafter set forth, of a signal device for use at a 15 railroad crossing, designed to be set by an approaching train to give warning to persons about to pass over the crossing and having means whereby the train after reaching the crossing will actuate a trip mechanism to remove the signal from view.

Another object of the invention is the provision, in a manner as hereinafter set forth, of a train actuated railway crossing signal which will be quick and positive in 25 action, strong, durable and efficient and inexpensive to manufacture and set up.

The invention will be best understood from a consideration of the following detailed description taken in connection with 30 the accompanying drawings forming a part of this specification, with the understanding that the invention is not confined to any strict conformity with the showing of the drawings but may be changed and modified so long as such changes and modifications mark no material departure from the salient features of the invention as expressed in the appended claims.

In the drawings:

40 Figure 1 is a top plan view of the signal device embodying this invention, showing the same in position at the side of a track at a crossing.

Figure 2 is a section taken upon the line 45 2—2 of Figure 1.

Figure 3 is a section taken upon the line 3—3 of Figure 1.

Figure 4 is a section taken upon the line 4—4 of Figure 1, and

50 Figure 5 is a section taken upon the line 5—5 of Figure 1.

Referring now to the drawings in detail wherein like numerals of reference indicate corresponding parts throughout the several 55 views, the numeral 1 indicates the usual

rails of a railroad line and the numeral 2 indicates the usual cross-ties which connect between these rails. At 3 there is indicated a portion of a roadway running at right angles to the track shown, the roadway 60 crossing the track as at 4.

The signal device embodying this invention comprises a plate 5 of substantial length and width, which is normally secured upon the end of a pair of the ties 2 adjacent one 65 of the rails and a substantial distance from the crossing at which the signal device is to be placed. This base plate 5 has a longitudinally extending upstanding rib 6 formed along its outer side edge and further has a 70 groove 7 formed in the top surface thereof extending longitudinally and running parallel with the rib 6. As shown in Figure 1 the plate 5 has the outer edge thereof cut to run at an angle with respect to the inner edge and with respect to the rail 1 which is parallel with the inner edge and the rib 6 and groove 7 run parallel with this angled outer edge. Formed upon the top of the plate 5 is a pair of blocks 8 and 9 respectively 75 the outer edges of which are in alignment as shown and are spaced from, and cut at an angle to run parallel with the inner side of the rib 6. There is thus set up between the outer edges of the blocks 8 and 9 and the 80 inner edge of the rib 6 a guide-way 10.

Pivotaly mounted upon the plate 5 between the blocks 8 and 9, is a gear wheel 11 carrying an up-standing pin 12 upon the upper side thereof and adjacent the periphery. This pin 12 has the upper portion 90 of reduced diameter as indicated at 13 and fitted about this upper portion is a revolute collar 14 held upon the pin by means of a nut 15 which is threaded upon the upper 95 end of the reduced portion. As will be seen from a further description of the device the gear wheel 11 is designed to oscillate and does not make a complete revolution at any time and the pin 12 with roller 14 carried thereon is arranged upon that portion of the wheel which lies adjacent the rails 1.

Arranged in the guide-way 10 is a rack bar 16 having formed upon the longitudinal center throughout the length thereof and 105 upon the top and bottom side, the ribs 17. The rib 17 upon the lower side of the rack bar 16 is designed to fit in and move in the groove 7 as shown. The teeth of the rack bar mesh with the teeth of the gear wheel 11 110

as shown in Figure 1 and one end of the rack bar 16 is provided with a head 18 through which an aperture is formed.

Overlying the blocks 8 and 9, the rib 6 and the gear wheel 11 and rack bar 16 is a cover plate 19 which is secured upon the top of the blocks 8 and 9 and the rib 6 by means of the bolts 20, and this cover plate has formed in its under-face a groove 21 corresponding with the groove 7 in the plate 5 and designed to receive the rib 17 formed upon the top of the rack bar 16. A retaining pivot bolt 22 is passed through the cover plate 19 and through the hub of the gear wheel 11 into the lower plate 5 to pivotally secure the gear wheel in position. The inner edge of the cover plate 19 aligns with the inner edges of the blocks 8 and 9 thus leaving a portion of the gear wheel 11 uncovered. 20 This portion is the portion upon which the stud or post 12 and roller 14 is mounted.

Mounted in the road-way 3 at one side of the crossing, is a plate body 23 of a construction similar to the plate body 5. This 25 plate body has the rib 24 along the outer edge thereof, and the outer edge is set at an angle with respect to the track as in the case of the plate 5 and further the outer edge of this plate is parallel with the outer edge of the plate 5. The inner face of the plate 23 has a longitudinally extending groove 25 therein adjacent the inner edge of the rib 24, and the plate also has a pair of supporting blocks 26 and 27 thereon the inner 30 edges of which are spaced from the inner edge of the rib 24 and parallel therewith. In the guide-way 28 thus formed between the rib 24 and the inner edges of the blocks 26 and 27, a rack bar 29 is positioned and 35 this rack bar 29 is provided with centrally positioned longitudinally extending ribs 30 one upon the top and the other upon the underside thereof. The lower rib 30 works in the groove 25 formed in the base plate 23.

40 Pivotedly mounted upon the plate 23 between the blocks 26 and 27, is a combined pulley and gear wheel indicated generally by the numeral 31. The lower portion of this wheel 31 is formed to provide the gear 45 32 while the upper portion is formed to provide a pulley 33 which is of less diameter than the gear 32.

The shaft upon which this combined wheel 50 31 is mounted is indicated by the numeral 34 and as shown the lower portion of this shaft has a bearing in the plate 23 and the upper portion thereof is of substantial length and extends upwardly above the gear and terminates in a reduced squared portion 55 35.

Placed over the plate 23, upon the blocks 55 26 and 27 and the rib 24 is a cover plate 36, which covers the major portion of the member 31 and completely covers the rack bar 29. This plate is held over the lower plate

60 by means of the bolt 37 and this plate also has formed in the underface thereof a groove 38 similar to the groove 25 in the plate 23, in which the rib 30 upon the top of the rack bar 29 is located. This rack bar 29 like the 70 rack bar 16 has a head 39 upon one end, through which an aperture is formed. When the two plates 23 and 25 are properly positioned a connecting cable 40 is extended therebetween, one end of this cable being 75 connected to the aperture in the head 18 of the rack bar 16 and the other end being connected to the aperture in the head 39 of the rack bar 29. The rack bars thus connected are so arranged that upon movement of one 80 of the bars by its meshed gear wheel, the other bar will be shifted to actuate the gear wheel in mesh therewith.

Upon the upper end of the shaft 34, there 85 is fitted a standard 41 the lower end of which is provided with an axial recess to receive the reduced portion 35 therein, and upon this standard there is carried a signal flag 42 which is so arranged that, when the signal is inactive, it extends parallel with the roadway 3 and when the signal is actuated, the flag is turned to extend across the road, 90 as shown in Figure 1.

95 Mounted upon one end of one of the cross ties 2, lying between the plates 5 and 23 there is secured by means of the screws 43 a plate member 44. This plate carries upon the upper side thereof the bearing boss 45 upon which is pivotally mounted about a pivot pin 46, a signal returning pulley 47. 100 This pulley as shown, carries thereon adjacent the periphery thereof an upstanding lug 48 about which the roller sleeve 49 is positioned and held by the nut 50.

105 Extending between the pulley 47 and the pulley 33 upon the combined device 31 is a cable 51, one end of which is secured as at 52 to the pulley 47, while the other end thereof is secured to the pulley 33.

110 Mounted upon a low-hanging beam or other appropriate member such as that indicated by the numeral 52, carried by the engine passing over the track adjacent to which this signal device is positioned is a trip device indicated generally by the numeral 53. As shown this trip device is secured upon the underside of the beam and it comprises the block body 54 which is mounted upon the beam transversely of the rail 1 over which it lies and upon the underside of this block 54 at the outer end thereof there is positioned a stop member consisting of a depending portion 55 and a laterally extending horizontal portion 56. The free end of this horizontal portion 56 is directed 115 forwardly upon the device. At the other end of the block 54 upon the underside thereof is a similar stop member having a depending portion 57 arranged upon the opposite side of the block member from the 120 125 130

portion 55 and also having a right angled horizontal portion 58 which is directed toward the rear of the device.

Pivottally secured against the under side 5 of the block 54 by means of the bolts 59 is a trip arm 60, the rear portion of which overlies the horizontal portion 58 of the stop at the inner end of the block and the forward portion of the trip arm overlies the 10 horizontal portion 56 at the outerside of the block 54. From this construction it will be readily seen that the trip arm can be swung in one direction only upon its pivot 59 to arrange it at right angles with respect to the 15 supporting block 54 and if it is swung in the opposite direction it will be stopped by the stop members to be held in a position parallel with the supporting block 54. This parallel position is the normal position of 20 the trip arm 60 and in order to maintain it in this position under normal conditions a spring 61 is provided, one end of which is attached to the eye 62 mounted upon the arm and the other end is attached to the eye 63 25 mounted upon the underside of the beam 52.

As clearly shown in Figure 1 the outer end of the trip arm 60 extends a slight distance beyond the rail 1 over which it lies and is adapted to contact with the stud and 30 roller 12 and 14 carried upon the gear 11 and also with the stud and roller 48 and 49 carried upon the pulley 47.

The operation of this signal device is as follows:—

35 With the signal device normally in off-position, the parts are arranged as shown in the plan view forming Figure 1 of the drawings, the signal flag being parallel with the road 3 upon which the base 23 is mounted.

A train moving along the track 1, being provided with the trip arm and other mechanism associated therewith, moves to the point where the outer end of the trip arm 60 will contact with the roller 14 carried upon the stud 12 and owing to the immovable condition in which the trip arm 60 is held by means of the stops 55 and 57, the gear wheel 11 must be revolved as the arm 45 presses against the roller stud carried thereon. Upon the revolution of this gear wheel 11, the rack bar 16 will be drawn backwardly through the passage 10 pulling upon the cable 40 thus drawing the rack bar 29 in the same direction. As will be clearly seen the movement of this rack bar will thus cause the combined gear wheel and pulley device 31 to be partially revolved and when this occurs the cable 51 will be drawn to partly 55 revolve the pulley wheel 47 to bring the roller carrying stud 48 in position alongside of the track 1. The revolving of the gear and pulley member 31 of course causes the shaft 34 to revolve thus swinging the flag 42 to a position transversely of the road 3.

As the train continues to move forward the trip arm 60 will arrive at the point where it must hit the roller and studs 48 and 49 carried upon the pulley 47 thus causing the pulley to be revolved in the opposite 70 direction and reversing the movement of the gears 11 and 32 and their associated rack bars 16 and 29, thus swinging the flag 42 back into inoperative position and returning the stud and roller member 12 and 14 75 to a position adjacent the rail where it will be again actuated by another train moving over the rails.

As will be readily seen the manner in which the arm 60 is mounted, enabling it to 80 be swung to a position transversely of the supporting block 54, will allow the train carrying the trip mechanism to back past the trip stud 12 without damaging the same for, when the train backs the outer end of 85 the arm 60 will hit the trip stud but will be swung from against the stop members 55 and 57 to such a position that it will be able to pass by the stud without injuring the same. After passing the trip stud 12 the 90 spring member 61 will cause the arm to be swung back to its original position as shown in Figures 2 and 6.

In view of the foregoing description it 95 will be readily seen that there has been provided an improved type of automatic highway signal which will be sure and accurate and unfailing in action.

Having thus described my invention what I claim is:—

1. A railroad crossing signal of the character described, comprising a connected rack and gear mechanism, a contact stud carried by said gear, a trip element designed to be carried by a train to strike said stud, a signal element, a rack and gear mechanism controlling said signal element, connecting means between the said mechanisms, and means operable by said trip element and connected with said last mentioned mechanism to restore the said signal element to non-signaling position after the setting of the same.

2. A railroad crossing signal of the character described, comprising a connected rack and gear mechanism, a contact stud carried by said gear, a trip element designed to be carried by a train to strike said stud, a signal element, a rack and gear mechanism controlling said signal element, connecting means between the racks of said mechanisms, and means operable by said trip element and connected with the gear of said last mentioned mechanism, to restore the signal element to non-signaling position.

3. A railroad crossing signal of the character described, comprising a connected rack and gear mechanism, a contact stud carried by said gear, a trip element designed to be carried by a train to strike said stud, a

- combined gear and pulley member, a rack bar in mesh with the last mentioned gear, an elongated upright shaft pivotally retaining said gear and pulley member in position, a signal flag carried upon the upper end of said shaft, and a connecting element between said racks for the control of the signal carrying gear by the rack and gear mechanism.
- 10 4. A railroad crossing signal of the character described, comprising a connected rack and gear mechanism, a contact stud carried by said gear, a trip element designed to be carried by a train to strike said stud, a
- 15 combined gear and pulley member, a rack

bar in mesh with the last mentioned gear, an elongated upright shaft pivotally retaining said gear and pulley member in position, a signal flag carried upon the upper end of said shaft, a connecting element between said racks for the control of the signal carrying gear by the rack and gear mechanism, and an oscillatory member adapted to be actuated by said trip and connected with said pulley member to restore 20 the signal to non-signaling position at the proper time.

In testimony whereof, I affix my signature hereto.

CHARLES GRAGERT.
